(57) **CLAIM**

The ornamental design for a flexible beverage container with opaque bottom, as shown and described.

DESCRIPTION

FIG. 1 is a front view of my new design for a flexible beverage container with opaque bottom;

FIG. 2 is a rear elevational view of the embodiment illustrated in FIG. 1;

FIG. 3 is a top view thereof;

FIG. 4 is a bottom view thereof;

FIG. 5 is a right side elevational view thereof;

FIG. 6 is a left side elevational view thereof;

FIG. 7 is a front elevational view of a second embodiment of my new design, the top and bottom views are as shown in FIGS. 3 and 4 respectively;

FIG. 8 is a rear elevational view of the embodiment illustrated in FIG. 7;

FIG. 9 is a left side view of the embodiment illustrated in FIG. 7, the right side being identical;

FIG. 10 is a front elevational view of a third embodiment of my new design, the top and bottom views are as shown in FIGS. 3 and 4 respectively;

FIG. 11 is a rear elevational view of the embodiment illustrated in FIG. 10; and,

FIG. 12 is a left side elevational view of the embodiment illustrated in FIG. 10, the right side being identical.
